UNITED STATES PATENT OFFICE

2,678,088

FURNITURE CONSTRUCTION

Henry D. Jamison, Jr., Nashville, Tenn.

Application April 30, 1951, Serial No. 223,768

6 Claims. (Cl. 155—196)

1

This invention relates to a novel construction of furniture, and more particularly to "over-stuffed" furniture of the living-room type.

Chairs and sofas have heretofore been designed for easy and quick assembly and disassembly for the purpose of facilitating the packing of the furniture for moving. However, the emphasis has been upon the "knock-down" feature of the construction rather than upon producing a stronger piece of assembled furniture.

The furniture construction of this invention has for its primary purpose the production of furniture which is actually more rigid and more resistant to breakage than conventional furniture but which also has the advantage of prior "knock-down" furniture of saving shipping cost and of being very easily assembled at the place of use.

My construction also makes possible the application of the prefabrication principle to over-stuffed furniture without any sacrificing of strength in the finished product.

Objects of the invention

It is an object of my invention to provide a piece of furniture of the "over-stuffed" type, which can be shipped "knocked-down" for minimal shipping volume but which when assembled will be at least as strong as conventional furniture.

It is another object to provide an over-stuffed chair or sofa which may safely be shipped (knocked-down) in a cardboard carton.

It is a further object of my invention to provide a piece of over-stuffed living-room furniture in which the seat, the back and the arms are joined together in their lower portions by bolt-like fasteners (without the necessity of using cement or glue), and by hook-like means in their upper portions where bolts or screws could not be conveniently utilized due to the upper portions being covered by the upholstery.

These and other objects and advantages of the invention will become apparent as the description proceeds.

Detailed description

In the drawings:

Fig. 1 is an exploded perspective view of the frame structure of a chair or sofa, with the upholstery being shown in phantom.

Fig. 2 is a detailed view partly in section of one of the hook means for fastening each side of the back to one of the arms.

Fig. 3 is a detailed cross-sectional view of one of the bolt-and-nut fastening means.

2

Fig. 4 is an end elevational view showing the packaging of a two-cushion sofa in a card-board carton (shown in phantom).

With reference now to the drawings, the cushion-supporting seat or base member 1 is formed as a rectangular frame of four boards vertically on edge and joined at each corner in conventional manner, as by nails, screws, glue, etc. Within or across the top of the frame there may be provided the usual cushion-supporting springs (not shown) and to be rested upon such springs are the customary removable upholstered cushions 2 (shown in phantom).

The back of the chair or sofa comprises a rectangular frame formed of at least two vertical board members 4 and 5, a connecting top board 6 and a bottom board 7 securely joined so as to lie flat-wise of the extent of the back. The uprights 4 and 5 carry near their lower ends a board 8 extending forwardly so as to overlie the back of the base or seat portion 1. The board 8 is braced by two web-forming vertical boards 9 and 10 which carry on their upper edges two shelf-forming blocks 11 and 12, the outer extent of which overlie the rear ends of the tops of the two arm members, presently to be described. Two laterally extending wing-like boards 13 and 14 extend the surface of the uprights 4 and 5 to form foundations for the arm-overhanging upholstering of the back portion.

Each arm part comprises a base board 15, front and back uprights 16 and a top board 17, rigidly connected at their abutting ends. Vertically on edge and connected to the bottom and to the uprights is the frame-stiffening and anchorage bar 18, lying flush with the inner surface of the arm-forming frames 15, 16, 17. The inner edge of the rear upright 16 is provided near its upper end with a slot 19 (Figs. 1 and 2) into which hook-carrying plates 20 (commonly called bed-hooks) enter to fasten the back 3 to the arms. The bases of the hooks 20 are mounted in similar slots 21 formed in the edges of upright members 4 and 5 of the back 3, being held fixedly therein by pins 22. Similar pins 23 (Figs. 1 and 2) traverse slots 19 for hooking engagement by the bed-hooks 20. The bed hooks are preferably used only to connect the furniture sections in those places where bolts or screws could not easily be used.

Where the arm, base and back sections join below seat level, they are connected by bolts or screws 24 which pass thru aligned bores in the adjacent frame members. The bolts 24 preferably pass outwardly from the inside of the base or seat frame 1, for convenience. On the outer

faces of boards 7 and 18, disk-shaped nuts 25 are anchored over the bolt-receiving bores, as by nails 26 (Fig. 3) passing thru small nail-holes therein. Nuts 25 may lie in countersunk depressions, as shown in Fig. 3, to avoid bulging the back-covering upholstery 27. Countersinking in boards 18, however, would not be advantageous. Washers 28 under the heads of the bolts 24 are also optional but desirable.

Fig. 4 shows how efficiently a two-cushion sofa constructed after the teaching of my invention, may be packed for shipping in a conventional corrugated card-board carton. The carton, with flaps open at the right end, is shown in phantom.

In contrast to glued joints, my bolted joints are equally strong but much less breakable by impact or twisting. Also they may be easily tightened if loosened by long or severe use. Then too, damaged sections can be cheaply returned to the factory for replacement or repair.

Having thus described the invention, what I claim as new and desire to secure by Letters Patent of the United States is:

1. In furniture construction, a quadrilateral seat-supporting frame comprising at least four peripherally disposed bars rigidly joined together near their ends, at least the three of said bars forming the side and rear members of said seat-supporting frame being plank-shaped and having their intermediate dimension vertically oriented; a vertically disposed arm frame at each side of said seat-supporting frame, said arm frame comprising at least four bars rigidly joined near their ends, portions of said arm frame lying flatwise against a side of one of said lateral bars of said seat-supporting frame; an upright back frame comprising a bottom bar, a top bar and two vertically disposed end bars rigidly interconnected near their ends; the bottom portion of said back frame having surfaces adapted for lying flat against the rear face of the rear bar of said seat-supporting frame; pairs of easily detachable vertically interlocking hook-type connecting means for fastening the ends of said back frame to the upper rear portions of said arm frames; and screw-type connectors extending across the flat junctions between the abutted bars of said frames for connecting the lower portions of said arm and back frames to said seat-supporting frame and for preventing their relative vertical

movement and thus preventing unhooking of said hook-type connecting means.

2. A furniture structure according to claim 1 and in which said hook-type connecting means comprise metallic plates fastened in slots in one of said frame members and protruding therefrom, the protruding portions having hook-forming notches therein, said protruding portions entering slots in the abutting member of the adjacent frame, and pins traversing said last-mentioned slots for hooking engagement with said protruding portions of said connectors.

3. A furniture structure according to claim 1 and in which said screw-type connectors pass thru bores in the abutting frame portions, said bores snugly but movably embracing said connectors, said connectors additionally comprising enlarged heads thereon and nuts having threaded axial bores therein for compressing said frame members between said heads and said nuts.

4. A furniture structure according to claim 3 and in which said nuts are of plate-like form and have nail-receiving holes thru the peripheral portions thereof, and nails passing thru said holes and into adjacent bars of said frames, whereby said nuts are anchored over said screw-receiving bores in said bars in axial alignment with said bores.

5. A furniture structure according to claim 1 and in which said structure is a chair.

6. A furniture structure according to claim 1 and in which said seat portion is elongated laterally to form a seat adapted to hold a plurality of persons side by side.
